C. J. GRIFFITH.

RAILWAY CROSSING.

APPLICATION FILED AUG. 16, 1912.

1,114,749.

Patented Oct. 27, 1914.

UNITED STATES PATENT OFFICE.

CHARLES J. GRIFFITH, OF ST. LOUIS, MISSOURI.

RAILWAY-CROSSING.

1,114,749.

Specification of Letters Patent.

Patented Oct. 27, 1914.

Application filed August 16, 1912. Serial No. 715,429.

To all whom it may concern:

Be it known that I, CHARLES J. GRIFFITH, a citizen of the United States, residing at St. Louis, Missouri, have invented a certain new and useful Improvement in Railway-Crossings, of which the following is a full, clear, and exact description, such as will enable others skilled in the art to which it pertains to make and use the same, reference being had to the accompanying drawings, forming part of this specification, in which—

Figure 1 is a plan view of a pair of integral crossing rails constructed in accordance with my invention. Fig. 2 is an elevational view partly in section taken on the line 2—2 of Fig. 1. Fig. 3 is an enlarged cross sectional view taken on the line 3—3 of Fig. 2. Fig. 4 is an enlarged sectional view taken on the line 4—4 of Fig. 1. Fig. 5 is an enlarged cross sectional view taken on the line 5—5 of Fig. 1. Fig. 6 is a plan view of a crossing frog constructed in accordance with my invention. Fig. 7 is a plan view of a turnout rail section constructed in accordance with my invention. Fig. 8 is an enlarged cross sectional view taken on the lines 8—8 of Figs. 1 and 6.

My invention relates to new and useful improvements in railway crossings of the type shown in my Patent No. 1,049,575, issued January 7, 1913, the principal object of my present invention being to construct a railway crossing wherein the crossing rails are formed integral with each other in order to provide a very strong, rigid, and substantial structure, and the rail members of which crossing are of hollow triangular shape in cross section, thus providing a wide base that will readily resist all side strains and stresses, and the material forming the body portions of the rails being so disposed as to obtain the greatest possible strength with a minimum amount of material.

By my improved construction a crossing can be produced at less cost than a crossing of ordinary construction owing to the reduced amount of material used together with the absence of bolts, rivets, and like fastening devices, and my improved crossing has greater strength and rigidity than an ordinary type of crossing owing to the peculiar construction of the rails and the disposition of the metal therein.

A further object of my invention is to provide simple means on the ends of the in-

tegral crossing rails wherein ordinary railway rails may be readily attached to the crossing rails.

To the above purposes my invention consists in certain novel features of construction hereinafter more fully described and claimed.

Referring by numerals to the accompanying drawings, A designates the crossing rails, the same being formed integral with each other and each rail comprises a base plate 1, a pair of upwardly extending inclined webs 2, the upper ends of which are united and formed integral with said upper ends is a ball 3.

Formed integral with the side of each ball 3 is an upwardly curved longitudinally extending flange-guard 4, and the space 5 between this guard and the ball of the rail 75 forms the flange track traversed by the flanges of the car wheels.

The base plate 1 and the webs 2 are comparatively thin and by reason of their triangular arrangement a very strong and substantial hollow base is formed for the crossing rails which arrangement readily withstands side stresses and vibration.

Formed integral with the ends of the crossing rails are base plate extensions 1^a and web extensions 2^a and these extending portions serve as points of attachment for ordinary railway track rails B, and in order that said ordinary rails can be positioned between the web portions 2^a the sides of the 90 base flanges of the ordinary track rails are cut away as shown in Fig. 3 in order that the parts can be readily assembled.

The ordinary rails are fixed to the extensions 2^a by means of bolts or rivets 6. 95 Where hollow triangular rails are used as track rails extensions 7 are formed on their ends and these extensions enter the hollow end portions of the crossing rails and are attached thereto by means of bolts or rivets 100 8 (see Fig. 5).

In Fig. 6 I have shown a frog crossing constructed in accordance with my invention and in Fig. 7 is shown a turnout rail.

My improved construction enables me to 105 form a railway crossing having great strength and rigidity and a crossing that will materially reduce pounding and jarring resulting from the vibration due to the passage of car wheels over the crossing. By 110 forming the crossing rails integral all nuts, bolts, and like fastening devices which are

ordinarily used in fastening crossing rails to each other are dispensed with.

It will be readily understood that minor changes in the size, form and construction of the various parts of my improved device may be substituted for those herein shown and described without departing from the spirit of my invention, the scope of which is set forth in the appended claims.

10 I claim:

1. The herein described railway crossing comprising crossing rails formed integral with each other, each of which crossing rails comprises a base plate, a pair of inclined webs integral with the base plate and a ball integral with the upper ends of said webs the base plate and webs of each crossing rail being extended at the ends thereof to receive and serve as points of attachment for track rails.

2. The herein described railway crossing comprising crossing rails formed integral with each other, each of which crossing rails comprises a base plate, a pair of inclined webs integral with the base plate, a ball integral with the upper ends of said webs, and a flange-guard integral with said ball the base plate and webs of each crossing rail being extended at the ends thereof to receive and serve as points of attachment for track rails.

3. A railway crossing comprising integral crossing rails that are hollow and of triangular shape in cross section, and hollow

triangular extensions on the ends of said 35 rails adapted to receive the ends of adjacent track rails.

4. The herein described railway crossing comprising crossing rails that are formed integral with each other, each of said rails 40 comprising a base plate, a pair of inclined webs, a ball on top of said webs, and hollow triangular extensions at the ends of the crossing rails, which extensions are adapted to receive the end portions of adjacent track 45 rails.

5. A railway crossing composed of intersecting crossing rails, the bodies of which are hollow and of triangular shape in cross section, balls integral with the tops of said 50 hollow body portions and hollow triangular extensions at the ends of said rails, which extensions are adapted to receive the end portions of adjacent track rails.

6. A railway crossing comprising hollow 55 intersecting rails, the openings through which rails are triangular in cross section, and hollow triangular extensions of the ends of said rails for the attachment of the ends of adjacent track rails.

60 In testimony whereof I hereunto affix my signature in the presence of two witnesses, this 14th day of August, 1912.

CHARLES J. GRIFFITH.

Witnesses:
